UNITED STATES PATENT OFFICE.

WILHELM KELLER, OF RONSDORF, GERMANY.

LOOM FOR WEAVING WIRE FABRIC.

Application filed June 7, 1926, Serial No. 114,310, and in Germany March 3, 1925.

In machine sieves used in the manufacture of paper the type of weave employed in the sieves is such that the paper rests only on the separate warp threads. Consequently they are soon worn down, while the weft thread which is entirely surrounded by the warp threads is not subjected to any wear whatever.

According to the present invention the fabric of the sieve is woven in such a manner that the paper rests both on the warp threads and the weft threads, so that the wear is equally distributed over both threads. This is effected by the warp and the weft being each bent to the same extent. This arrangement provides the further advantage that a considerably more transparent paper is obtained, as the paper itself will rest on the weft and the warp, while with the present type of fabrics the paper rests only on the separate raised parts of the warp.

Machine sieves of this kind are made with an arrangement of a special kind, which forms the subject of the present invention, the arrangement consisting in providing guiding blades which are stationary and beat-up bars loosely guided between them. These beat-up bars are engaged by a slide at each end of the bar in the direction of width of the fabric and are beaten up against the fabric. In order that these bars shall beat up successively, the slide is provided with an upwardly inclined groove. This groove commences at the surface where the bars rest and terminates at the same surface, but is provided with a sharp edge at each end, to ensure the bars being picked up. Simultaneously with each part of the weft thread being beaten up the shed is formed in such a manner that, when the weft thread has been completely beaten up, the change of shed will already have taken place. The arrangement for changing the shed must thus work independently of the beating up arrangement. For this purpose two superposed wedge-shaped members are connected to the slide at each side, the wedges having their pointed ends facing each other and two of which always lie alternately in one plane. These two oppositely located wedge-shaped members actuate heddles, which guide the warp threads. Owing to the wedge-shape, the heddles are pushed laterally, so that the warp threads

held in them are forced to take part in this lateral displacement, the heddles resting against the wedge-shaped members in the upper plane being displaced in one direction, while the heddles resting on the wedge-shaped members in the lower plane are displaced in the opposite direction, whereby a shed is formed in the warp threads.

A constructional example of the arrangement according to the invention is shown in the accompanying drawing, Figure 1 being a diagrammatic representation of the woven wire fabric as seen from the front, Figure 2 a plan view of Figure 1, Figure 3 a front view of the arrangement for making the sieves according to Figures 1 and 2 with a picked weft and the slides in the position of rest, Figure 4 a front view of the arrangement with the weft picked and partly beaten up, Figure 5 a section on line 5—5 of Figure 4 and Figure 6 a section on line 6—6 of Figure 4. The separate warp threads *a* lying next to one another are connected together by the insertion of the thread *b*, forming a lower and an upper shed, the warp threads being bent by this means. The weft thread *b* is inserted between the warp threads in such a manner that it is also bent between the separate warp threads. This may for instance be effected by the weft thread not being pressed all at once into the fabric in the ordinary way by being beaten up by the reed, but by the sections of the weft thread lying between the warp threads being pressed separately against the fabric, a shed being formed at the same time. As will be seen from Figure 2, in this way of weaving in the portion of fabric cut off by the section lines *x*—*y*, twelve points of contact for the paper are established (1 to 12). The woven fabric according to the invention will thus only wear half as quickly as the fabric of the known kind. Furthermore the points of contact for the paper are closer together, so that in the case of thin paper the sieve markings are considerably reduced.

The arrangement for making the sieve is shown in Figures 3 to 6.

In a machine frame the two guiding reeds *s* and *t* are rigidly fixed in a vertical position. On either side of these reeds the two slides *d* and *e* slide in guiding rails *c*, which slides may be driven mechanically in any desired manner in a horizontal plane.

These two slides have at their upper edge guiding grooves *f* and *g* respectively which ascend and descend in the form of a wedge. In these grooves slide the ends of the beat 5 up bars *h* which are guided between the separate blades of the guiding reeds *s* and *t*. Each of the two slides also supports by means of the straps *i* two wedge-shaped pieces *k*, *m*, *n* and *l*, which lie one above the 10 other with their wedge-shaped ends facing each other. Against these wedge-shaped pieces the heddles *o* and *p* alternately rest, supporting the warp threads *q*. These heddles are also guided between the reed blades 15 of the two reeds *s* and *t*. The arrangement operates in the following manner:

When the weft thread *r* has been inserted, the slides *d* and *e* are moved along the two reeds *s* and *t*. The two slides by means of 20 their grooves *f* and *g* pick up the beat-up bars *h*, whereby the latter are raised separately between the reeds *s* and *t*, owing to the inclination of the guiding grooves (Fig. 4). By this raising of the bars *h* 25 the weft is beaten up successively from one side of the fabric to the other. During the forward movement of the slides *d* and *e* the wedge-shaped members *k*, *l*, *m*, *n* become operative, the wedge *m* pushing the 30 heddles *p* to the right and the wedge *l* the heddles *o* to the left and the shed being thus changed. On the slides moving in the other direction, the wedge-shaped members *k* and *n* become operative and again change 35 the shed. Each change of the shed between the reed blades is completed, when the heddles *o* or *p* respectively have travelled along the inclined surface of the corresponding wedge-shaped members and have reached the 40 flat portion of the wedge. At the same time at the same part of the fabric or between the same reed blades the weft thread will have been beaten up by the bars *h* which slide between the corresponding reed blades, 45 having travelled along the upwardly inclined part of the guide groove *f* and reached the straight portion thereof. Figure 5 shows the various parts in position, in which the weft thread *r* has just been 50 beaten up, the shed changed and a new shed has been opened for the next pick. It is of

course also possible to use the new arrangement on a loom, in which the warp lies horizontally.

What I claim is:

1. An apparatus for weaving machine sieves for use in the manufacture of paper, comprising in combination fixed reed blades, beat-up bars guided between the said reed blades, two slides in engagement with the 60 said beat-up bars, means for guiding the slides on either side of the woven fabric in the direction of its width, and means for forcing the said beat-up bars against the fabric, as set forth. 65

2. An apparatus for weaving machine sieves for use in the manufacture of paper, comprising in combination fixed reed blades, beat-up bars guided between the said reed blades, two slides in engagement with the 70 said beat-up bars, means for guiding the slides on either side of the woven fabric in the direction of its width, means for forcing the said beat-up bars against the fabric, said means comprising an arched groove in each 75 slide terminating in a sharp edge at either end at the surface on which the beat-up bars rest, as and for the purpose set forth.

3. An apparatus for weaving machine sieves for use in the manufacture of paper, 80 comprising in combination fixed reed blades, beat-up bars guided between the said reed blades, two slides in engagement with the said beat-up bars, means for guiding the slides on either side of the woven fabric 85 in the direction of its width, means for forcing the said beat-up bars against the fabric, a plurality of heddles for guiding the warp threads, and two superposed wedge-shaped members connected to each 90 slide, said members being adapted to engage said heddles to form a shed.

4. An apparatus for weaving sieves as claimed in claim 3, the faces of said wedge-shaped members being in fixed relation to 95 the arch groove, so that a maximum size shed will be formed adjacent the top of said arched groove.

In testimony whereof I affixed my signature.

WILHELM KELLER.
